US0D1079367S

(12) **United States Design Patent** (10) **Patent No.:** **US D1,079,367 S**
(45) **Date of Patent:** **** Jun. 17, 2025**

(54) **COOKER**

(71) Applicant: **SENGOKU WORKS, LTD.**, Kasai (JP)

(72) Inventors: **Takehira Sengoku**, Kasai (JP); **Akihiko Shirota**, Kasai (JP)

(73) Assignee: **SENGOKU WORKS, LTD.**, Kasai (JP)

(**) Term: **15 Years**

(21) Appl. No.: **29/857,591**

(22) Filed: **Oct. 24, 2022**

(30) **Foreign Application Priority Data**

May 18, 2022 (JP) ..... 2022-010588 D

(51) **LOC (15) Cl.** **07-02**
